UNITED STATES PATENT OFFICE.

JOHN LINCOLN GISH, OF SOUTH BEND, INDIANA.

REGULATED AUTOMATIC-CLOSING VALVE.

1,033,002.

Specification of Letters Patent.

Patented July 16, 1912.

Application filed December 28, 1910. Serial No. 599,774.

To all whom it may concern:

Be it known that I, JOHN LINCOLN GISH, a citizen of the United States, residing at South Bend, in the county of St. Joseph and 5 State of Indiana, have invented a new and useful Regulated Automatic-Closing Valve, of which the following is a specification.

The object of my present invention is to construct a "regulated automatic closing valve", in such a manner, firstly, that the water in the tank will be retained under direct pressure, until the said water is required for flushing; secondly, that the water in the tank will be discharged in a large 15 volume, under direct pressure, into and through the valve-casing; thirdly, that the flushing stream, after passing the outlet in the valve-casing, performs no other work or function, but that of flushing; and fourthly, 20 after the flushing has been completed, for the "regulated automatic closing valve", to be closed automatically, the apparatus be ready, to repeat its work, as hereinafter described.

25 Figure 1, is a perspective of my improved apparatus. Fig. 2, is a vertical section thereof, with the valves D., and K., in the closed position. Fig. 3, is a vertical section thereof, with the valve D., open, and the valve K., 30 closed. Fig. 4, is a vertical section thereof, with the valves D., and K., in the open position. Fig. 5, is a vertical section thereof, with the valve D., closed, and the valve K., 35 open. Fig. 6, shows the regulating plate R., adjusted to a different position, in order to regulate a shorter flushing stream.

In the drawings, self closing valves, of the reciprocating type are shown.

Like letters of reference, refer to like 40 parts, in the several figures.

In Fig. 1.—E., is the tank, fastened fluid-tight, to the removable valve-casing T. I., is the inlet, to the tank E. T., is the valve-casing. P., is a face plate, fastened fluid-tight, to the valve-casing T. R., is a regulating plate; p., is a stop pin, in the regulating plate R.; s., is a slot in the regulating-plate R.; ss., is a set screw, which fastens the regulating plate R., to the face plate P. H., is 45 a handle; C., is a counterbalance, to handle H. a., is a set nut, joining the handle H., to an operating spindle, which passes through the face plate P. O., is the outlet to the valve-casing T. The usual connec-

tions with the service pipe, and the discharge pipe, are made at I., and O., respectively. A., is a supporting arm, projecting from the inside of the valve-casing T., and engaging the spindle S. S., is an operating spindle, which passes through the face plate 55 P., (Fig. 1,) at a. B., is a finger, firmly fixed, upon the spindle S. d., is a valve stem, to the valve D. D., is the relief valve, to the valve K. d', is the valve seat, to the valve D., in the valve K. z., is the conduit, 60 from d', through the valve K., at some point removed, from the central axis of the valve K. m., is an adjustable weight, attached to the valve stem d., by the set pin i. K., is the main valve; K', is its flat valve seat, in the 65 valve casing T. T', is a removable casing, which incloses the main valve K., and forms a part of the valve casing T. O', is an inlet, to the casing T', from the tank E. X., is a chamber, in the casing T', above the 70 valves D., and K.

The special features of my device are described as follows:—The main valve K., is a heavy weighted valve (not buoyant) which slides up and down in the valve-casing T., 75 in such a manner, so that it is only, by or with great pressure, that air or water, can be forced or filtered, between the outer wall of the valve K., and the inner wall of the casing T'. The said valve K., has a concave bottom, so as to form an annular ring, 80 on the bottom of the said valve K.; and the said annular ring contacts the flat valve-seat K'.

The weighted vent-valve D., is recessed, 90 in the top of the valve K., and its solid stem d., projects through the main valve K. The solid stem d., is so constructed, that it slides, so snugly, up and down, in its passage way, 95 through the valve K., that when the vent-valve D., is opened, no air or water, escapes along the line, of the valve-stem d. Hence, by such a construction, with no lateral motion, to the solid stem d., the valve D., with its recessed valve-seat d', is assured of a 100 positive seating, upon its valve-seat d', providing the adjustable weight m., is attached to the valve-stem d., by the set pin i., as will be explained below.

With such close coadaptation of surfaces, 105 of the valve D., and its solid valve-stem d., with the valve K., and yet give complete ventilation to the valve D., when opened, it

is necessary to provide a conduit, through the valve K., at some point removed from the central axis of the valve K.; which said conduit will begin at the lower edge of the 5 valve-seat d',, and open or end, in the bottom of the valve K.; as for example, the conduit zz.

As to the adjustable weight m., which is attached to the valve-stem d., by the set pin 10 i., the said weight m., performs special work, besides acting as a stop, to limit the distance, the valve D., is raised from its valve-seat d',, or to act as a part of the 15 means, which raises the valve K., after the valve D., has been opened;—namely, the said weight m., is the force or means, which draws quickly, the valve-stem d., back to its starting position, thereby assuring a quick and positive reseating of the valve D., after 20 the means, for opening the valve D., has broken contact, with the valve-stem d.; and also, after the valve D., has been reseated, by the action of the weight m., the said weight m., holds the vent-valve D., upon its 25 valve-seat d',, as the main valve K., descends to its valve-seat K',, thereby offering a great resistance to the air, which is trying to re-enter the chamber X., through the conduit zz., and the valve-seat d',, as the main valve 30 K., descends to its valve-seat K'.

In the act of the opening of the valves D., and K., we displace through the conduit zz., the air and water, that may have been confined within the chamber X. Now, by a pre- 35 arranged relation of parts, we allow the valve D., to close, and leave the valve K., suspended within the casing T',, see Fig. 5. This suspended relation, of the heavy weighted valve K., Fig. 5, is in proportion, 40 to the assembling of the parts, T',, K., D., d., and m.; whereby we govern, the balancing of the force of gravity, which acts upon the valves, and the pressure beneath said valves. And this is accomplished, by hav- 45 ing the device so constructed, and the parts so assembled, that it is only, by or with great pressure, that air or water, can be forced or filtered, into the chamber X., between the outer wall of the valve K., and the inner 50 wall of the casing T',, and since air, cannot easily or quickly, re-enter the chamber X., by way of the conduit zz., and the valve-seat d',, by reason of the fact, that the valve D., is held down, upon its valve-seat d',, by 55 the weight m., which is attached to the valve-stem d., it is readily seen, that we have a gradual control, over the air, which is trying to re-enter the chamber X., thereby giving us a gradual, regulated, self closing of 60 the valve K. You will notice that I say,— control over the air, which is trying to re-enter the chamber X. The reason for this statement is,—that when the valve K., begins to close, the tank E., is practically 65 empty of water, and the valve K., being so

far removed from its valve-seat K',, there is nothing but air, to find its way, into the chamber X. And also by way of reference, would say, that the device is so formed, that the contents of the tank E., is expelled, at 70 some little time, before the valve K., is closed, thereby allowing for an extra amount of water, to flow from the inlet I., into the tank E., and to pass directly, to and through the valve-seat K',, and thus serve, as the 75 quantity of water needed, to refill the closet bowl, after the closet bowl has been flushed, and before the valve K., is closed.

The means, employed to open the valves D., and K., becomes a feature,—not in the 80 way the valves D., and K., are opened; but as soon as the valves D., and K., are opened, the said means, by releasing the operating handle H., breaks contact, see Fig. 5., with the said valves, and allows the immediate 85 closure, of the valve D., by means of the weight m.; thus performing a specific act or function, in leaving the valve K., suspended in the casing T',, see Fig. 5., for a predetermined time, in order to regulate, the self 90 closing of the valve K.

With the special features thus described, my device, performs its work as follows: In Fig. 2., the valves D., and K., are in the closed position. Water is allowed to enter 95 the tank E., through the inlet I. Into the said tank E., water will flow, until the air, within the tank E., has been compressed, to an equal degree, with the water pressure, from the service pipe. As the tank E., is 100 filled with water and compressing the air therein, as soon as the air and water pressure, within the tank E., has become of a sufficient pressure, to overcome, the resistance, that is offered, to either air or water, by the close coadaptation of the outer wall 105 of the valve K., and the inner wall of the casing T',, then and not before,—water passing through O',, will be forced between the two said surfaces, of the valve K., and casing T',; and this forced filtration, between the outer wall of the valve K., and the inner wall of the casing T',, will be continued, until the air within the chamber X., will be of the same compression, as the air 110 within the tank E. This compression of air and water, within the chamber X., will force the valve K., downward, upon its valve-seat K',, and assure a positive closure, of 115 said valve K.

In Fig. 3., the operating means, H., S., and B., are shown, as having opened the valve D., and thereby relieved the chamber X., from its pressure of confined air and water; said air and water having been discharged, through the valve-seat d',, and the conduit zz., downward, through the valve-seat K'. The quantity of water, that has 120 been confined, within the chamber X., is so small, that it is not considered of a flush- 125

ing nature. Now, with the pressure removed from the chamber X., by the opening of the valve D.,—a full downward motion of the handle H., will operate the means, H., S., B., d., and m., which will easily push the main valve K., upward into the chamber X., and away from the valve-seat K', Fig. 4., and allow the contents, of the tank E., to pass into the opening O', and directly 10 through the valve-seat K', into the discharge or flushing pipe, at O; and in the act of discharging,—the water in the tank E., is forced into the flushing pipe, under the heavy compression of air, aforesaid, that 15 has been confined within the tank E.

As soon as the valve K., Fig. 5., has been pushed up into the casing T', and the handle H., is released, the counter-balance C., returns the handle H., which rotates the 20 spindle S., to which is firmly fixed the finger B., back to their starting position; thereby breaking contact, with the valve-stem d., which act, allows the immediate closure of the valve D., by means of the 25 weight m., which is attached to the valve-stem d., and leaves the valve K., suspended within the casing T', as shown in Fig. 5.; and as stated above, the valve K., Fig. 5., will descend slower or faster, in proportion, 30 to the assembling of the parts, T', K., D., d., and m., and thereby return the parts, to their respective positions, as shown in Fig. 2., and leaves the device ready, to repeat its work.

The regulating means R., s., ss., and p., performs its work as follows:—In Fig. 6., the dotted lines, show position of the regulating plate R., adjusted so that the handle H., can make a full downward motion and 40 open the valve K., to its fullest extent, for a full flushing stream, before the handle H., comes in contact, with the stop pin p. Now in order to make a shorter flushing stream, the regulating plate R., is adjusted as shown 45 in Fig. 6., bringing the stop pin p., closer to the starting position of the handle H., thereby limiting the downward motion, of the handle H.; and the shorter we make the downward motion of the handle H., by the 50 re-adjusting of the plate R., the shorter will be the opening of the valve K., and the shorter, the opening of the valve K., the shorter the flushing stream, will be.

From the above description, it will be 55 noticed, that the first, second, third, and fourth objects, of my present invention, as above mentioned, are fully accomplished.

What I do claim as my invention, and desire to secure, by Letters Patent is,—
60 1. In a regulated automatic closing valve, the combination of a direct pressure tank, provided with the inlet and outlet passages, and adapted to retain fluid, under direct pressure, in said tank, until said fluid is re-

quired for flushing; a valve casing provided 65 with inlet and outlet passages, to allow a flushing stream, to pass through said valve casing, and said valve casing adapted to inclose a self closing reciprocating valve, so that a confined chamber X., is formed above 70 said reciprocating valve; a weighted self closing reciprocating valve, within the said valve-casing, said self closing reciprocating valve, adapted to offer great resistance, to either air or water, that tries to pass, between the inner wall of the said valve-casing, and the outer wall of the said reciprocating valve; said reciprocating valve provided with a concave bottom, forming an 75 annular ring, said ring forming the contact 80 surface, with the flat valve-seat K'; a conduit through the said reciprocating valve, at a point removed from the central axis of said reciprocating valve, and adapted to be opened and closed by a vent-valve; a 85 vent-valve provided with a recessed valve-seat d', and a valve-stem d., projecting through the central axis of the said reciprocating valve, said valve-stem d., adapted to prevent fluid passing along the line of the 90 said valve-stem d., and provided with an adjustable weight m., attached to the said valve-stem d., at a point below the under surface of the said reciprocating valve, to assure the positive closure of the said vent-valve; and means, co-operating with the said 95 valve-stem d., to open the valves D., and K., and adapted to break contact with the said valve-stem d., as soon as the said valves 100 D., and K., are opened.

2. A regulated automatic closing valve, provided with a direct pressure tank having inlet and outlet openings and adapted to retain fluid, under direct pressure, in said tank, until said fluid is required for flushing,—the combination of a valve-casing having inlet and outlet openings to allow a flushing stream to pass through said valve-casing, said valve-casing inclosing a main self closing reciprocating valve, so that a confined chamber is formed above said reciprocating valve; said main reciprocating valve adapted to offer great resistance to either air or water that tries to pass between the inner wall of the said valve-casing and the outer wall of the said main reciprocating valve, said main reciprocating valve provided with a concave bottom forming an 110 annular ring which contacts with the valve-seat; a conduit through said main reciprocating valve at a point removed from the central axis of said main reciprocating valve and adapted to be opened and closed by a vent-valve; said vent-valve having a valve-stem projecting through the central 115 axis of said main reciprocating valve entirely filling the aperture through which it passes, to prevent fluid passing along the 120 125

line of said valve-stem and also provided with an adjustable weight attached to the said valve-stem at a point below the under surface of the said main reciprocating valve 5 to assure closure of the said vent-valve; in combination with means coöperating with the said valve-stem to open the said vent-valve and the said main reciprocating valve, and adapted to break contact with the said 10 valve-stem as soon as the said vent-valve

and the said main reciprocating valve have been opened.

In testimony whereof I have signed my name to this specification in the presence of two subscribing witnesses.

JOHN LINCOLN GISH.
